SPRAY DRIER

Alan C. Stoneman, San Marino, Calif., assignor to
 Purex Corporation, Ltd., South Gate, Calif., a
 corporation of California

Application January 24, 1949, Serial No. 72,427

12 Claims. (Cl. 159—4)

1

This invention has to do generally with drying systems operable to separate and substantially solidify materials out of fluid mixtures or solutions by vaporization of the liquid solvent or carrier. Particularly the invention is directed to improvements in spray drying equipment wherein a fluid or slurry composition containing the material to be recovered is subjected to extended surface contact with air and resultant concentration of solids, by spraying the liquid downwardly within a chamber and concurrently or countercurrently with a drying air stream.

As illustrative, the invention is applicable to the spray drying of materials capable of solidification in the form of hollow globular, porous or cellular particles characterized by their friability, and hence requiring carefully controlled handling to prevent their disintegration and dusting. Typical of such materials are solidifiable detergents including various soaps and wetting agents, such as the aliphatic sulphates and sulphonates, alkyl aryl sulphonates, generally the sulphated or sulphonated petroleum derivatives, or derivatives of alcohols, ethers, esters or amids, etc. Also contemplated is the cooling or drying of proteins (e. g. eggs) and the like, as well as inorganic substances such as various salts, e. g. carbonates and borates.

One of my major objects is to provide for such rapid drying and cooling of the product as will prevent deterioration of all materials subject to physical or chemical impairment if held at elevated temperatures, say within the range of 200° F. to 350° F., for an extended period of time.

Also particularly contemplated are improvements in a continuous course of drying whereby the product is conditioned against physical deterioration during and following its collection from the spray drier, by first assuring its reduction to a state of substantially completed dryness or rigidity, in the absence of which the product may be subject to excessive dusting. It is found that where required cooling of the product is permitted to continue after collection of the particles on a conveyor or thereafter in storage, marked deterioration occurs by reason of such effects as lumping, and weakening of the particle structure upon crystallization of its salts (typical in the case of solid detergents) as cooling and drying proceed to completion. In accordance with the invention, the product particles are subjected to such rapid and complete cooling and drying while in divided or suspended condition as to assure attainment of the desired final structure and condition of the particles in advance of

2

their collection and storage. Thus the product may quickly attain not only a stable physical form but also chemical stability immediately upon drying, thus avoiding degradation (e. g. nutritionally) of such products as the amino acids, which suffer from being subjected to excessive or prolonged heating.

The invention has the further and important practical advantage of substantially increasing the capacity of a given size drier, in that the ability to accomplish quick and thorough final drying of the product all in a continuous drying sequence, permits a material throughput considerably greater than the capacity of the conventional drier whose throughput is primarily limited by its inability to accomplish final drying comparably in time or thoroughness.

Structurally, the invention is directed primarily to final drying of the product after its travel down through a spray chamber during which the bulk of the liquid content of the material may have become vaporized and the product approaches substantially solid form. The invention is predicated upon the concept of then contacting the product with such quantities of atmospheric air as may be required for quick cooling and drying, and while the particles are caused to have such gentle falling motion as will prevent their disintegration. Specifically the particles falling from the spray chamber are directed desirably in a series of downwardly cascading streams, preferably of annular form, transversely through which streams of atmospheric air are passed, as by induction into a chamber at the inside of the stream series.

All the features and objects of the invention, as well as the details of certain illustrative embodiments, will be understood more fully and to best advantage from the following detailed description of the accompanying drawing, in which:

Fig. 1 is a view showing in side elevation a spray drier representing one embodiment of the invention, certain portions of the structure appearing in section;

Fig. 2 is a fragmentary enlargement of the bottom portion of the structure shown in Fig. 1; and

Fig. 3 is a fragmentary sectional view illustrating a variational embodiment of the invention.

Referring first to Fig. 1, the drier comprises a shell 10 forming a vertically extended drying chamber into the top of which is either induced or forced from conduit 11 a flow of air which passes downwardly through the chamber as hereinafter described, to the induction outlet conduit

12. The fluid solution or slurry to be dried may be introduced to and dispersed within the chamber in any suitable manner, typically by spraying the solution from circularly arranged nozzles 13 within the head of the chamber and from which the slurry is discharged in a state of droplet division in accordance with the desired product particle size. The air or gas entering the chamber through the inlet 11 may be preheated so that the bulk of the liquid or water content of the slurry will become vaporized into the air stream during the course of their concurrent flow to the bottom of the chamber.

The drying chamber bottom is formed by an inverted frusto-conical section 14 having a discharge opening 15 from which the air stream is discharged into an annular space 16 within the concentrically spaced, frusto-conical outer duct or jacket 17. Upon entering the space 16, the air stream undergoes a flow reversal so that by virtue of gravity and inertia effects, the incompletely dried product particles travel on downwardly to the bottom of the secondary chamber 18. The induction conduit 12, which may be connected to a suction blower (not shown) communicates with the air passage 16 at circularly spaced intervals through the series of ducts indicated at 19.

As previously indicated, upon discharge from the spray chamber through opening 15, the particles have lost most of their liquid content but nevertheless may be still sufficiently cohesive that if permitted directly to drop onto the conveyor 20 and thence taken to storage while in heated and incompletely dried condition, the particles would tend to lump together and deteriorate upon crystallization of their salts, all as mentioned in the introduction. Also if given no accelerated cooling, certain classes of materials would undergo chemical impairment as a result of prolonged maintenance of the particles at elevated temperatures. Accordingly, in order to insure the product against either physical or chemical degradation, I provide at the bottom of the secondary chamber 18 a cooling arrangement generally indicated at 21 which assures immediate completed solidification and chemical stabilization of the product.

Referring now to Fig. 2, opening 22 in the bottom of the air jacket 17 contains a vertical coaxial conical baffle 23 centered with relation to the axis of opening 15 so that the product particles, excepting those reduced to dust size being withdrawn in the air streams going to the ducts 19, fall upon and are uniformly deposited about the baffle 23. Below this baffle is a series of suitably supported angularly reversed conical baffles 23, 24 and 25, three being shown as typical, in coaxial alignment with a fourth baffle 26 discharging into the collector baffle 27 and thence onto the conveyor 20. Thus annular streams of the product flow from opening 22 downwardly in a series of cascading streams in passing over the baffle series 23 to 27 and in falling through the spaces between them. The baffle angularities and their diameters preferably are such in relation to the quantity of material flowing over them, that the material is subjected to such low viscosity and gentle deflecting effects as not to rupture the hollow bead-like or globular form of the particles, thus reducing any dusting tendencies to a minimum.

In the course of its cascading flow downwardly over the baffle series, the product is cooled by mechanically created drafts of atmospheric air flowing transversely through the product stream

falling between the baffles. The air flow may be induced, as through a pipe 30 leading to the same or a different suction source (e. g., suction blower 131) than the blower connected to conduit 11, the pipe having open end branch 31 extending vertically and centrally within the baffle series and containing a series of openings 32 into which the air flow is induced at the opening locations along the pipe. Air turbulence within the cone 23 may be prevented by a plurality, typically four, of radial vanes 33 extending from the pipe 31 to the conical baffle wall.

By controlling the rate of air induction into the pipe, the rate of atmospheric air flow inwardly through the baffle series and cascading product streams may be so controlled as to effect quick final cooling of the product to the temperature desired, while simultaneously drying the particles to give them the necessary hardness that will prevent any consequential cohesion or disintegration at and beyond their deposition on the conveyor.

Fig. 3 illustrates a variational embodiment of the invention, according to which the passage of final drying and cooling air through the product beyond the spray chamber outlet 15, is effected by atmospheric air induction into chamber 18. Here I may use instead of the previously described continuous wall baffle 23, a suction of spaced conical baffles 133, 34 and 35 positioned within the bottom outlet end of the jacket 17 and in axially centered relation to the chamber outlet 15 so that the product is permitted to fall uniformly over the baffle series and in cascading streams from each to the baffle below. The reduced pressure in chamber 18 causes the induction of atmospheric air upwardly within the baffle series 133, 34 and 35, and outwardly through the spaces 36 and 37 between them, and of course transversely, but in this instance outwardly through the cascading particle streams. From the lower baffle 35, the product may be dropped onto the conveyor 38, or otherwise collected.

It will be understood that the drawings are to be regarded as illustrative of the invention in certain of its typical and preferred forms, and that various changes and modifications may be made without departure from the invention in its intended spirit and scope.

I claim:

1. A spray drier comprising a vertically extended shell forming a drying chamber and having a bottom converging to a discharge opening, means for spraying within said chamber in contact with drying air therein, liquid particles passing downwardly within the chamber to be dried to substantially solid particles, baffle means at said opening extending transversely of the path of the falling particles and forming and directing a stream of incompletely dried particles downwardly from said opening, there being a cooling space below said baffle extending about an inside zone and through which the particles fall, a blower and a conduit connected to the blower and terminally positioned in proximate relation to said cooling space so that cooling air is displaced through the cooling space and the falling stream from one side to the other side thereof.

2. A spray drier comprising a vertically extended shell forming a drying chamber and having a bottom converging to a discharge opening, means for spraying within said chamber in contact with drying air therein, liquid particles pass-

ing downwardly within the chamber to be dried to substantially solid particles, baffle means at said opening extending transversely of the path of the falling particles and forming and directing a stream of incompletely dried particles downwardly from said opening, there being a cooling space below said baffle extending about an inside zone and through which the particles fall, a blower, and a conduit connected to the blower and communicating with said zone so that cooling air is displaced through said cooling space from about said falling stream inwardly therethrough into said zone.

3. A spray drier comprising a vertically extended shell forming a drying chamber and having a bottom converging to a discharge opening, means for spraying within said chamber in contact with drying air therein, liquid particles passing downwardly within the chamber to be dried to substantially solid particles, a vertical series of baffles extending transversely of the path of the falling particles positioned at and directly below said opening, there being cooling spaces between said baffles so that incompletely dried particles pass downwardly in a succession of cascading streams over the baffles and through the cooling spaces and in a pattern extending about an inside zone, a blower and a conduit connected to the blower and terminally positioned in proximate relation to said cooling spaces so that cooling air is displaced through the cooling spaces and the cascading streams from one side to the other thereof.

4. A spray drier comprising a vertically extended shell forming a drying chamber and having a bottom converging to a discharge opening, means for spraying within said chamber in contact with drying air therein, liquid particles passing downwardly within the chamber to be dried to substantially solid particles, a vertical series of baffles extending transversely of the path of the falling particles and exposed openly to the atmosphere at and directly below said opening, there being cooling spaces between the baffles so that incompletely dried particles pass downwardly in a succession of cascading streams over the baffles and through the cooling spaces and in a pattern extending about an inside zone, a blower, and a conduit connected to the blower and communicating with said zone so that atmospheric air is drawn through said cooling space from about said cascading streams inwardly therethrough into said zone.

5. A spray drier comprising a vertically extended shell forming a drying chamber and having a bottom converging to a discharge opening, means for spraying within said chamber in contact with drying air therein, liquid particles passing downwardly within the chamber to be dried to substantially solid particles, an upwardly convergent circular baffle within said opening forming and directing a stream of incompletely dried particles downwardly from said opening, there being a cooling space below said baffle extending about an inside zone and through which the particles fall in an annular stream, a blower and a conduit connected to the blower and terminally positioned in proximate relation to said cooling space so that cooling air is displaced through the cooling space and radially and uniformly through said annular stream from one side to the other side thereof.

6. A spray drier comprising a vertically extended shell forming a drying chamber and having a bottom converging to a discharge opening,

means for spraying within said chamber in contact with drying air therein, liquid particles passing downwardly within the chamber to be dried to substantially solid particles, an upwardly convergent circular baffle within said opening and an annular baffle directly below and spaced from said circular baffle to form a cooling space between the baffles, incompletely dried particles being directed by said circular baffle in an annular stream falling through said cooling space onto said annular baffle and about a zone within the baffles, and blower and conduit means communicating with said zone and operating to draw atmospheric air inwardly through said cooling space and stream into said zone.

7. A spray drier comprising a vertically extended chamber having a bottom converging to a discharge opening, means for spraying downwardly within said chamber a liquid to be dried to substantially solid residual particles, means for passing drying air through said chamber, an upwardly convergent substantially conical baffle within said opening onto which incompletely dried particles are deposited from said chamber and from which the particles are dropped in an annular stream, a plurality of spaced coaxial frusto-conical baffles of reverse angularity below said opening and conical baffle and over which the particles fall in a succession of cascading streams, and a suction blower communicating with and drawing air from the interiors of said baffles and inducing separate streams of air inwardly between the baffles and radially inwardly through said stream.

8. A spray drier comprising a vertically extended chamber having a bottom converging to a discharge opening, means for spraying downwardly within said chamber a liquid to be dried to substantially solid residual particles, means for passing drying air through said chamber, an upwardly convergent substantially conical baffle within said opening onto which incompletely dried particles are deposited from said chamber and from which the particles are dropped in an annular stream, a plurality of spaced coaxial frusto-conical baffles of reverse angularity below said opening and conical baffle and over which the particles fall in a succession of cascading streams, and an induction pipe extending into a space within said baffles, air being drawn from the atmosphere inwardly between the baffles and through said streams into the induction pipe.

9. A spray drier comprising a vertically extended shell forming a drying chamber and having a bottom converging downwardly to an upper discharge opening, means for spraying downwardly within said chamber a liquid to be dried to substantially solid residual particles, said shell including a downwardly convergent wall spaced about said bottom of the chamber and having in its bottom a lower discharge opening and having also a suction outlet through which a flow of drying air is induced downwardly through the chamber, upwardly convergent baffle means axially aligned with said upper discharge opening and positioned in said lower discharge opening and in spaced relation to the wall edge forming the opening, and a conduit communicating with the inside of said baffle means and through which a flow of atmospheric air is induced transversely and inwardly through a stream of incompletely dried particles deposited on and falling from said baffle means.

10. A spray drier comprising a vertically ex-

tended shell forming a drying chamber and having a bottom converging downwardly to an upper discharge opening, means for spraying downwardly within said chamber a liquid to be dried to substantially solid residual particles, said shell including a downwardly convergent wall spaced about said bottom of the chamber and having in its bottom a lower discharge opening and having also a suction outlet through which a flow of drying air is induced downwardly through the chamber, upwardly convergent baffle means axially aligned with said upper opening and positioned in said lower opening and in spaced relation to the wall edge forming the opening, atmospheric air flow being induced to said suction outlet through a falling stream of incompletely dried particles deposited on said baffle means.

11. A spray drier comprising a vertically extended shell forming a drying chamber and having a bottom converging downwardly to an upper discharge opening, means for spraying downwardly within said chamber a liquid to be dried to substantially solid residual particles, said shell including a downwardly convergent wall spaced about said bottom of the chamber and having in its bottom a lower discharge opening and also having a suction outlet through which a flow of drying air is induced downwardly through the chamber, upwardly convergent baffle means axially aligned with said upper opening and positioned in said lower opening and in spaced relation to the wall edge forming the opening, a plurality of spaced coaxial frusto-conical baffles of reverse angularity below said conical baffle and over which the particles fall in a succession of cascading streams, and an induction pipe extending laterally into a space within said baffles and thence upwardly therein, air being drawn from the atmosphere inwardly between the baffles, and through said streams into the induction pipe.

12. A spray drier comprising a vertically ex-

tended shell forming a drying chamber and having a bottom converging downwardly to an upper discharge opening, means for spraying downwardly within said chamber a liquid to be dried to substantially solid residual particles, said shell including a downwardly convergent wall spaced about said bottom of the chamber and having in its bottom a lower discharge opening and having also a suction outlet through which a flow of drying air is induced downwardly through the chamber, upwardly convergent baffle means axially aligned with said upper opening and positioned in said lower opening and in spaced relation to the wall edge forming the opening, a plurality of spaced coaxial frusto-conical baffles of reverse angularity below said conical baffle and over which the particles fall in a succession of cascading streams, and an induction pipe extending laterally into a space within said baffles and thence upwardly therein, air being drawn from the atmosphere inwardly between the baffles, and through said streams into the induction pipe.
